CLAIM

The ornamental design for a central processor for an electronic computer, as shown.

DESCRIPTION

FIG. 1 is a front, top and left side perspective view of a central processor for an electronic computer showing our new design;

FIG. 2 is a front elevational view thereof;

FIG. 3 is a rear elevational view thereof;

FIG. 4 is a right side elevational view thereof;

FIG. 5 is a top plan view thereof; and

FIG. 6 is a bottom plan view thereof;

FIG. 2

FIG. 3

FIG. 4

FIG. 5

FIG. 6
